UNITED STATES PATENT OFFICE.

WILHELM HOLL, OF WINTERTHUR, SWITZERLAND.

LOCK FOR UMBRELLA-STANDS.

SPECIFICATION forming part of Letters Patent No. 739,180, dated September 15, 1903.

Application filed January 3, 1903. Serial No. 137,710. (No model.)

To all whom it may concern:

Be it known that I, WILHELM HOLL, a subject of the German Emperor, residing at Winterthur, Switzerland, have invented certain new and useful Improvements in Locks for Umbrella-Stands, of which the following is a specification.

The subject of the present invention is a lock for umbrella-stands which renders impossible the unauthorized removal of the umbrella, walking-stick, or the like placed therein by securing the umbrella in its place by the arm of an angle-lever held in the locking position. This lever can only be rotated for freeing the umbrella on the introduction of a specially-formed key.

In the accompanying drawings, Figure 1 shows a plan view of the umbrella-stand provided with the lock; Fig. 1^a, a front view thereof. Fig. 2 shows in plan the interior arrangement of the lock. Fig. 3 is a section on the line a b, Fig. 2. Figs. 4, 5, and 6 show the tumblers of the lock in side and plan view. Figs. 7 and 8 show the lock-detent in side and plan view. Fig. 9 is a section on the line C'D of Fig. 7. Figs. 10 and 11 show the locking-lever in plan and side view, and Fig. 12 shows the key employed.

As can be seen from the drawings, the lock-case b is secured to the cast body-piece a by screws x x. In this case b are arranged the locking-lever c and the sliding-detent d. Transverse to the direction of movement of the detent d there are arranged above the latter the tumblers l l l², which are under the action of spiral springs o o' o². (See Figs. 2, 4, 5, and 6.) Under the effect of these springs the tumblers can so be moved in either direction that the openings m m' m² on sliding toward the right come out of engagement with the projection h of the detent d, Figs. 7, 8, and 9, while the tumblers forced to the left enter into the recesses u u of the detent d and in this manner prevent the longitudinal sliding of the detent, as now the angle-lever c is in engagement by means of its toothed sector z' with the toothed portion z of the detent d. In this position, as can be seen from Fig. 2, the angle-lever c is locked. As soon, however, as the key i, Fig. 12, is introduced through the guide f' into the recesses k k' k² of the tumblers l l l² the latter, in consequence

of the special formation of the recesses k k' k² and of the key i, will be forced aside in both directions. When the key i has been inserted as far as possible, the tumblers l l l² will so be pushed aside under the action of the springs o o' o² that the rolled projections s s of the recesses k k' k² of the tumblers enter into corresponding recesses in the key i. The openings m m' m² of the tumblers are hereby so actuated that the detent d or its projection h can be freed, whereby the locking-lever c can be rotated through a right angle for opening the lock. While the detent d is being slid the projection h remains in engagement with the recesses m m' m² of the tumblers, so that an unauthorized removal of the key i from the openings or recesses k k' k² is prevented, since the tumblers are also locked against sliding and the rolled projections s remain in engagement with the corresponding recesses of the key i. As soon as on inserting an umbrella or walking-stick the arm of the angle-lever is again rotated through a right angle, owing to the engagement of the teeth z z', the detent d will be brought out of connection with the tumblers l l l², which on withdrawing the key are moved to either side under the influence of the springs o o' o² in such a way that the recesses m m' m² of the tumblers lock the projection h of the detent d in its position. The angle-lever c will hereby be brought into the locking position, so that the umbrella inserted will be completely secured against unauthorized removal. In order to secure the lock in its open or in its closed position, the spring n is provided, which so acts upon a nose t' of the locking-lever c that the latter is certain to snap into one position or the other.

What I claim, and desire to secure by Letters Patent of the United States, is—

1. In an umbrella-stand, the combination with a suitable casing, of an angular locking-lever formed with a toothed sector, a sliding recessed detent having teeth to engage those of the sector, and a series of tumblers adapted to be locked and released from engagement with the recesses in the detent, substantially as shown and described.

2. The combination in an umbrella-stand; with a casing, of an angular locking-lever formed with a toothed sector, a sliding re-

cessed detent having teeth to engage those of the sector, and a series of spring-actuated tumblers, all adapted to operate substantially as set forth.

- 5 3. In an umbrella-stand, the combination with a casing, of a series of recessed tumblers, an angular lever having a toothed sector formed thereon, a sliding recessed detent provided with teeth for engagement with those on the sector, and a projection for engagement with the recesses in the tumblers, all adapted to operate substantially as described.
4. An umbrella-stand, comprising a suit-

able casing, an angular toothed lever, an actuating-spring, a sliding toothed and recessed detent having a projection thereon, a series of recessed tumblers adapted to be locked or released by a suitable key, all constructed and adapted to operate substantially as shown 15 and described.

In testimony whereof I have hereunto set my hand in the presence of two witnesses.

WILHELM HOLL.
